UNITED STATES PATENT OFFICE

2,180,976

FILM CUT-OUT

Henry E. Butler, Scotia, N. Y., assignor to General
Electric Company, a corporation of New York

Application March 18, 1936, Serial No. 69,494

12 Claims. (Cl. 200—118)

My invention relates to dielectric film cutouts and more particularly to cutouts for series connected lamps.

This application is a continuation in part of 5 my application Serial No. 32,043, filed July 17, 1935.

One application of my invention is in connection with strings of series connected lamps such as are used in the lighting of Christmas 10 trees or for other decorative purposes wherein it is common practice to connect eight or nine lamps in series across the usual 115 volt house lighting circuit. When one of these lamps burns out, each one of the lamps in the string is extinguished and it becomes necessary to try each lamp to determine which one is burned out. It is also found at times, after duly testing each lamp in a circuit, that the lamps are all good but that one of the lamps had become loose in its socket 15 and thereby broke the circuit.

It is one of the objects of my invention to provide an improved cutout device for shunting the circuit around a burned-out lamp in a series circuit.

Another object of my invention is to provide a 25 cutout which will simultaneously act as a locking device for locking the lamp in its socket.

Another object of my invention is to provide a method of manufacturing cutouts whereby only 30 a single film of oxide is placed between the two terminals of a circuit.

Another object of my invention is to provide a cutout for series connected lamps which will establish a circuit when the voltage across the 35 lamp contacts reaches a predetermined value and will again interrupt the circuit when the current in said circuit rises to a predetermined value.

Other objects and the advantages of my invention will be apparent and the invention itself 40 will be better understood from the following description, when considered in connection with the accompanying drawing, and the features of novelty which characterize my invention will be pointed out with particularity in the claims annexed to and forming a part of this specification.

In the accompanying drawing, Figs. 1 and 2 45 illustrate respectively a plan view and a side view of an oxide film cutout made in accordance with 50 my invention; Fig. 3 illustrates one of the cutouts illustrated in Figs. 1 and 2 mounted on the base of an incandescent lamp; Fig. 4 illustrates the lamp of Fig. 3 assembled in a socket; Fig. 5 is an enlarged sectional view of a lamp 55 base having thereon a cutout made in accordance

with my invention; Fig. 6 illustrates a method of manufacturing the cutouts; Fig. 7 is a circuit diagram illustrating the usual series string of eight lamps connected to a plug cap through a fuse, and Figs. 8, 9, 10, 11 and 12 are modifications of my invention.

Referring to the drawing in detail, Figs. 1 and 2 illustrate a thin metal concave disk 10, having attached thereto ears 11 and 12 projecting in opposite directions from the disk. The disk 10 is provided with a concentric truncated cone portion 13 having an outwardly rolled edge 14. This metal disk is covered with a layer 15 of metal oxide which forms the dielectric film. The metals most generally used for this purpose are copper or aluminum. Other suitable metals may, of course, be used. The process of applying an oxide coating to this metal is important, since the thickness of the oxide determines the breakdown potential. It is also necessary to provide 15 an oxide which will not flake off when the cutout is bent while being assembled on the lamp base. One satisfactory process for producing this oxide film on copper is disclosed in United States Patent 1,982,384, to Edgar H. Harty and assigned 20 to the assignee of the present invention.

As stated above, the metal of the cutout, illustrated in Figs. 1 and 2, is thin and easy to bend. In placing the cutout on the base of an incandescent lamp, lamp 16 for example, the truncated cone section 13 is fitted against the similarly-shaped insulation section 17 of the lamp base extending between the metal screw shell 18 and the center contact 19. The ears 11 and 12 are then bent at right angles to the disk 10 30 downwardly along the screw shell 18 and a rubber band 20 is rolled over the base so as to hold the cutout onto the base until the lamp is screwed into a socket 21. This is clearly illustrated in Figs. 3 and 4.

To explain my invention I have illustrated 40 lamp 16 as being equipped with a base comprising a screw shell and a raised center contact at the end thereof. This type of base is referred to in the art as an "Edison type" base. It will be 45 clear to those skilled in the art that my cutout can be equally applied to modifications of this base without departing from the spirit of my invention.

The center contact 19 on the illustrated lamp 50 base comprises a drop of soft metal, such as solder, which is deposited when the lamp lead is anchored in the base. The rolled edge 14 of the cutout touches this center contact along its edges, as is illustrated in Fig. 5, but the center portion 55

of this contact projects above the rolled edge so that when the lamp 16 is screwed into the socket 21, the center contact 19 engages the center contact 22 of the lamp socket. The threads of the screw shell 23 in the socket 21 force the ears 11 and 12 into the grooves of the screw shell 18 of the base. This is done without breaking the ears 11 and 12, because the metal itself is made flexible enough and because the socket and the base are made with sufficient clearance between them to permit the lamp base being easily screwed into the socket, until the last fraction of a turn, before it becomes tightly seated in the shell.

15 In operation, or actual use, it is an easy matter for any inexperienced person to place the cutout on a small base of a Christmas tree lamp, as above explained. When the lamp is then placed into a socket, the ears 11 and 12 do not prevent contact between the shells 18 and 23, because they are not wide enough, but they do act in the capacity of a lock washer and prevent the lamp becoming loose in the socket due to a jarring of the socket. In case the filament in the 25 lamp breaks, the circuit between the contact 19 and the shell 18 is broken, so that the full line voltage, that is, the full voltage available at the outlet from which current is drawn for the Christmas tree circuit, is placed across the 30 oxide film between the contact 19 and the rolled edge 14 of the cutout. In the treatment of the cutout, this oxide film is made of such thickness that it will break down at about one-half of the available voltage. When this film breaks 35 down, the metal of the cutout becomes a conductor between the shell 18 and the center contact 19 of the lamp, to take the place of the filament, and the circuit through the remaining lamps is again established. It will be noted that 40 in order to establish this conductive path, current must enter the metal of the ears 11 or 12 and again leave at the edge 14. If the entire cutout, including the ears 11 and 12, is covered with oxide, it will be necessary for the potential to 45 break down two layers of this oxide. This may be desirable in cases where a single layer of oxide is insufficient to carry the desired voltage. On the other hand, the ears 11 and 12 need not necessarily be oxidized, and if not, then it is 50 only necessary for the potential to break down the single layer of oxide between the rolled edge 14 and the center contact 18 of the lamp. In such instances the thickness of the single layer of oxide may be more easily controlled 55 and the breakdown voltage thereby more accurately obtained.

In the production of oxide-coated cutouts, it has been found difficult to produce a continuous or dependable oxide coating along the edges 60 of the thin sheet metal which for the present use is between 2 and 3 thousandths of an inch. In my present cutout I overcome this difficulty in one instance and make use thereof in another instance. It will be noted that the inner edge 65 14 of the truncated cone section 13 of the disk 10 is rolled, or flared outwardly, and that it is the continuous inner surface of the cone that touches the center contact 19 of the lamp base. The faulty edge is out of contact.

70 In making the cutouts in large numbers, I prefer to use a large sheet of metal 24, such as shown in Fig. 6, and produce the truncated cone sections 13 and rolled edges 14 spaced from each other at predetermined distances. The 75 sheet is then treated to produce the oxide thereon

and thereafter is cut along the dotted lines 25, as indicated. This last step leaves an unoxidized edge on both the disk and the strips. When the lamp base having thereon one of these cutouts is screwed into a socket, the oxide which is weak at the severed edges is sufficiently displaced to permit the metal of the strips engaging the socket shell. The only insulation between the shells and the center contacts is, therefore, one thickness of oxide between the rolled edge 14 and the 10 center contact 19.

Fig. 7 is a circuit diagram illustrating the manner of connecting the lamps 13 and cutouts 10 in a series circuit to a plug cap 31. A fuse 32 is placed in the circuit to prevent the current rising above 15 the safe limit when several of the lamps in the circuit burn out. It is to be noted that since the available voltage remains substantially constant, the voltage across each lamp rises when one burns out. The possibility of the other lamps 20 burning out is, therefore, increased. To avoid this difficulty I provide several modifications of the above described cutout.

25 In Fig. 8, I have illustrated one modification of my invention. The cutout illustrated in this figure is suitable for larger lamps and comprises an oxide-covered disk 26 provided with a hole 27 suitable for the center contact of a lamp base to project through. A pair of straps 28 and 29 are fastened to the edge of the disk and are 30 respectively fastened to a resilient split ring 30. This structure is placed on the base of a lamp and the oxide on the edge of the hole 27 constitutes the insulating film. When the filament 35 breaks the coating breaks down and establishes a circuit, between the screw shell and the center contact, through the material of the disk 26. This material may be a low resistance metal, such as copper or aluminum, or it may be a high resistance metal or other material so as 40 to take the place of the burnt-out lamp filament. It is to be noted that in this construction the disk is manifold the thickness of the disk 10 wherefore the precaution of rolling the edge of hole 27 is not necessary, although it could 45 be done if found necessary. The straps 28 and 29 are not oxide coated. Any suitable method 50 may be used to attach the straps to the disk. The method illustrated comprises slotting the disk after the oxide coating process so that the straps placed through the slots will contact the metal 55 of the disk. In this manner only the single oxide coating at the edge of hole 27 controls the breakdown.

55 In Figs. 9, 10 and 11 I have illustrated a modification of my invention whereby the cutout serves also as a fuse for interrupting the circuit through the remaining lamps. In Fig. 9 I have illustrated a modification comprising a rectangular portion 33 provided with a hole 34 through which the center contact of a lamp may project. A strap 35 provided with a reduced portion 36 is attached to the rectangular member 33. The member 33 corresponds to the member 10 of Fig. 1 and the strap 35 corresponds to the strap 12. 60 When this latter cutout is used the member 33 is cemented to the center contact of the lamp and the strap may either be cemented or held by a rubber band 20. When the lamp burns out the oxide breaks down and if the current rises 65 above the predetermined safe value, the portion 36 will fuse and break the circuit. With this modification I retain the advantage of the strap for locking the lamp in its socket and obtain the additional advantage of providing a fuse within 70

the lamp socket. In manufacturing this modification I use strip material having a width equal to the width of the rectangular portion 33. This provides a considerable saving of material over 5 the method used for the manufacture of the cut-out of Figs. 1 and 2.

Figs. 10 and 11 illustrate another modification in which an oxide coated metal strap, or wire, 37 is attached to the center contact of the lamp and 10 to the shell. The strap 37 is made of such dimensions that it will carry only a predetermined current and will fuse and break the current circuit when a larger current flows. The lower side may be fastened to the upper end of the shell 15 contact. If so attached the cut-out has the two functions of establishing a current circuit when the lamp burns out and to break the circuit when the current exceeds a predetermined value. When this strap extends along the shell and is attached 20 thereto at the lower end it also acts to lock the lamp into the socket. In view of the fact that this strap is weak and may be broken when the lamp is inserted in the socket, a large strap similar to strap 35 may be combined with the strap 25 37. In attaching this strap 37 to the center contact of the lamp, this contact is grooved and the oxide-coated strap is soldered therein. In case the lamp burns out the oxide breaks in the solder and permits current to flow in the metal of the 30 strap. When the lamp is turned into the socket the oxide film on the strap is rubbed off sufficiently to permit the current to flow directly to the shell. In manufacturing this cut-out, a continuous wire or strip is oxidized and then cut 35 into the required lengths. One end of this strip is placed into the groove in the metal of the center contact so that the bare end is free of the lamp contact, as shown in Fig. 14; the other end may be connected to the bulb of the lamp or 40 to the shell, as above described.

In Fig. 12 I have shown a modification wherein in a resistance wire 38 is wound in the grooves of the shell. It is attached at its one end to the shell and at its other end to an oxidized strap 39 45 which is attached to the center contact of the lamp in the same manner as strap 37. In this manner the proper breakdown and fusing strength is obtained. The resistance of the wire is chosen such that the length wound about the 50 shell will have sufficient resistance to take the place of the burned-out lamp. The wire 38 is covered with enamel which insulates the wire and has sufficient strength to resist abrasion during the turning of the lamp into the socket. In 55 this manner the current flows from the oxide-coated strip 39 to the resistance wire 38, through the wire and to the shell at the end of the wire where it is soldered to the shell and the insulation removed.

60 What I claim as new and desire to secure by Letters Patent of the United States is:

1. A dielectric film cutout for use with a lamp having a center contact and a shell, comprising a current conducting member coated with a dielectric film, arranged to engage the center contact of a lamp base and to extend over a portion 65 of the shell surface of the said base for establishing a circuit between said contact and said shell upon the breaking of said film due to the occurrence of a predetermined voltage and for locking said base in a socket.

2. A dielectric film cutout comprising a coated metal disc arranged to engage the center contact of a lamp base, and current conducting means 70 arranged to extend along the side of the shell of

a said base to hold said disc in engagement with a said center contact.

3. A dielectric film cutout comprising an oxide coated current conducting disc arranged to engage the center contact of a lamp base and provided with an opening through which a said center contact may project, and current conducting means attached to said disc arranged to extend along the shell of a said base and for holding said disc in engagement with a said center contact. 10

4. In combination, a lamp provided with a base, comprising a shell and a second contact insulated therefrom and projecting above the end of said shell, a dielectric film cutout comprising 15 a coated metal disc in engagement with the said second contact of said base, said disc being provided with an opening through which said second contact projects, means for holding said disc in engagement with said second contact comprising 20 a pair of flexible metal strips attached to said disc and engaging the shell of said base, and a flexible collar surrounding said shell and strips for holding said strips in engagement with said shell. 25

5. An oxide film cutout comprising an oxide film coated metal disc provided with centering means for engaging the center contact of a lamp base the metal of said disk being spaced from said center contact by said oxide film, said base comprising a shell and center contact, current conducting straps attached to said disc and adapted to engage the shell of a said base, said straps being free from oxide on their edges whereby contact may be established between a 30 shell and the metal of said straps so that only a single film of oxide insulates a said center contact from a said shell. 35

6. In combination, a lamp provided with a base comprising a shell and center contact, a dielectric film cutout comprising a coated disc of current conducting material in engagement with said center contact, a pair of current conducting straps attached to said disc in engagement with the shell of said base, and a rubber band surrounding said shell and straps for holding 45 said straps in engagement with said shell.

7. In combination, a lamp provided with a base comprising a shell and center contact, a socket therefor, a dielectric film cutout for shunting 50 said contacts in case the filament of said lamp breaks comprising a dielectric film coated current conducting disc in engagement with the center contact of said base, and means for holding said disc in engagement with said base including a flexible current conducting strap attached to said disc, said strap being pinched between said base and said socket when said lamp is inserted whereby said strap acts to lock said lamp in said base. 55

8. In combination, a lamp provided with a base, contacts in said base normally insulated from each other, a cutout comprising a dielectric film covered and fusible current conductor adjacent said contacts, said cutout being arranged 65 to establish a current conducting circuit between said lamp contacts upon the occurrence of a predetermined rise in voltage between said contacts and to fuse and thereby break said established circuit upon the occurrence of a predetermined increase in current flowing in said circuit. 70

9. In combination, a lamp provided with a base, contacts in said base normally insulated from each other, and a cutout comprising a cur- 75

- rent conducting member provided with an insulating film for separating it from one of said contacts and being attached to the other of said contacts, and having a resistance substantially equal to the normal resistance of said lamp.
5. 10. In combination, a lamp provided with a base comprising a center contact and a screw shell contact, said contacts being insulated from each other and comprising the terminals of said lamp, and a cutout comprising an insulated wire having a total resistance substantially equal to the normal resistance of said lamp adjacent at one end to the said center contact being separated therefrom at this end by an insulating film having a predetermined breakdown voltage, said wire being wound about said shell and attached to the shell at its other end.
10. 15. A dielectric film cutout comprising a coated current conducting member arranged to engage the center contact of a lamp base, an insulated resistance wire attached to said member at one end and wound in the grooves of the screw shell of a said base, said wire having a resistance sub-
15. 20. 20. resistance wire attached to said member at one end and wound in the grooves of the screw shell of a said base, said wire having a resistance sub-

stantially equal to the resistance of a said lamp and attached at its other end to the said shell whereby this cutout establishes a shunt circuit of equal resistance to the lamp when a predetermined potential occurs across the contacts thereof, breaks this circuit upon the occurrence of a predetermined current and locks the said lamp base in a socket.

12. In combination, a lamp provided with base contacts, an insulating member between said contacts, a cutout comprising a dielectric film covered and fusible current conductor adjacent said contacts and extending along the surface of said insulating member between said contacts, said cutout being arranged to establish a current conducting circuit between said lamp contacts upon the occurrence of a predetermined rise of voltage between said contacts and to fuse and thereby break said established circuit upon the occurrence of a predetermined increase in current flowing in said circuit.

HENRY E. BUTLER.
